MOORING DEVICE

Fredrick W. Coffing, Danville, Ill.

Application April 15, 1947, Serial No. 741,473

5 Claims. (Cl. 114—230)

1

This invention relates to a mooring system for boats.

The chief object of the present invention is to provide a mooring structure for the mooring of boats so that a person can readily enter and leave the boat by merely stepping out of the same onto a dock, pier, breakwater, etc., and which boat will be so moored that not only will it rise and fall with the tide, but if it should fill due to wave action or a leak, the boat will not sink, and of course, when properly moored the boat will not rub or strike the dock, pier, etc., to which it may be then moored.

The chief feature of the present invention resides in providing in combination with an upright a boom hingedly mounted adjacent same, and a supporting member in the form of a chain connecting the upright and boom to limit the extent of lowering of the boom, there being provided a parallel partial connection of spring type included with the supporting member, the boom supporting a pulley, in turn supporting a boat connected line, which line can be tied to the boom near its hinge pivot axis or to the boom support adjacent thereto.

Other objects and features of the invention will be set forth more fully hereinafter.

The full nature of the invention will be understood from the accompanying drawings and the following description and claims:

In the drawings the figure is a perspective view of the end of a pier provided with a pair of booms, one being shown in the extended position and the other being shown in the withdrawn or collapsed position, a boat operatively associated therewith, the tie lines and the spring-cable structures associated therewith.

In the figure, 10 and 11 indicate uprights such as projecting piles forming a part of a support such as a pier or dock having stringers 12, planking 13 and cross member 14 at the end. There are provided two mooring structures 15—16, each associated with one of the piles. Since the booms are herein shown for convenience, the same, except reversed, the detailed description of but one should suffice for both. Also since same are illustrated as disposed at the end of a pier they are embodied in right triangular form with the hypotenuses adjacent each other and the effective bases in substantial alignment. When, however, the mooring structures are applied to a sea wall, dock or breakwater they may partake of isosceles or other triangular form, all without departing from the basic invention.

The extended boom comprises member 15 and angular disposed member 16, both of rigid, non-

2

flexible material, suitably secured together as at 17, the former being extended as at 18. This portion mounts an anchorage 19 and a swivel eye 20, the latter supporting pulley housing 21, the wheel 22 therein supporting rope or cable 23.

The outer end of rope 23 is arranged to be secured to bow anchorage 24 of the boat 25. The stern may be similarly anchored by stern anchorage 26 on the boat. On the pier or dock adjacent post 11 or on member 13 there is fixed rope anchor member or cleat 27 to which the land end of rope 23 may be secured.

Each member 15 and 16 may be independently and hingedly mounted on horizontal axes as at 15 28 and 29 respectively to the support or pier. The hinge connection is such as to permit the outer ends of the booms to swing freely in vertical directions, both above and below the level of the pier or wharf. If desired the adjacent ends 20 of the members 15—16 may be suitably connected together and the connection double hinge mounted on the pier end or side.

To anchorage 19 near the end of boom member 15 is permanently secured to one end 30 of 25 a supporting member such as link chain 31. The other end is secured by a lag screw 32 or a plurality thereof to upright or pile 11 forming a part of the support. A tension spring 33 may have one end permanently affixed to the upright 30 as at 34 and the other end has a suitable fastening device that can detachably connect the spring to any one of the chain links within reach of the spring. The spring can have both ends detachably connected to the chain.

Thus the chain and spring normally support the boom so that it is properly disposed at all times. As the incoming tide raises the boat the spring elevates the boom and takes up the chain slack so that the rope 23 is taut at all times, 40 thus holding the boat away from the pier, etc. As the tide falls the free end of the boom also falls, due to the weight of the boat attached thereto, this movement being permitted by the spring 33 which at all times compensates for any tendency toward slack in the chain 31.

In the event the boat fills by reason of rain, waves or a leak and endeavors to sink, all cable slack is let out and the spring is extended, the boom then holding up the connected end of the 50 boat to prevent sinking thereof. It will be noted that the supporting cable 31, while permitting the boom to swing below horizontal position, will hold the boom sufficiently high to prevent the boat coming in contact with the wharf or piles 55 when in submerged condition.

As shown in its "collapsed" position, the boom

is tilted upwardly upon its pivotal support and the spring 33 anchored at 34 now is engaged with chain 31 near its post anchored end and the intermediate portion of said spring envelopes the boom to constrain it to vertical position and hold it therein.

Also the cable 23 secured at the land end at 27, adjacent to the hinged connection of the boom, not only passes over pulley wheel 22 on the vertical boom but its boat end is secured to stern anchor 26 on the boat. These anchorages 26 and 24 are centrally disposed at the ends of the boat so that the boat does not tip or tilt but rises and falls with the tide.

As shown in the drawing the stern cable 23 may be drawn inwardly to position the boat stern immediately contiguous to the dock or pier, for getting into and out of the boat or for loading or unloading purposes.

Obviously both booms are normally disposed in the upright position when the boat is not moored at the pier. This removes obstructions from the channel.

In anchoring the boat it is run up to the dock or pier, the forward cable 23 is pulled through the pulley and tied to the bow anchorage 24. The stern cable 23 is similarly handled and tied to stern anchorage 26. When the occupants leave the boat, the booms are released from the springs 33 and the respective chains at 35 attached to the spring ends at the proper position so that at low tide the boat will be supported by the slightly tautened chains, the booms then being extended.

The cables 23 are then tightened up so that the boat is pulled away from the dock. As previously described, if the boat tends to sink, the springs, chains and cables will hold it up and prevent sinking. Also as the tide rises the boat rises therewith and springs 33 hold the booms progressively elevated in accordance with tide elevation, the chain between upright 11 and spring anchor 35 slackening. Cables 23 accordingly remain relatively taut at all times. In this position the boat is moored away from the dock.

When the boat is to be used cable 23 is untied at 27 to allow slack in cable 23 and stern boom is lifted or elevated and then the boat is pulled to the dock by cable 23. The bow boom can then be elevated or left extended as desired and the bow cable cast off.

While the invention has been illustrated and described in great detail in the drawings and foregoing description, the same is to be considered as illustrative and not restrictive in character, reference being had to appended claims.

The invention claimed is:

1. In a boat mooring device, a support, a mooring boom pivoted on a generally horizontal axis of appreciable length at its inner end to said support whereby the outer end thereof swings freely in vertical directions, a supporting member connected at one end to the free end of said boom and at its other end to said support above said boom, a yieldable element in said supporting member whereby the latter extends or retracts, and means on the free end of said boom to detachably secure a boat thereto.

2. In a boat mooring device, a support, a mooring boom pivoted on a generally horizontal axis of appreciable length at its inner end to said support whereby the outer end thereof swings freely in vertical directions, a flexible member connected at one end to the free end of said boom and at its other end to said support above said boom, a spring in said flexible member whereby the latter extends or retracts, and means on the free end of said boom to detachably secure a boat thereto.

3. In a boat mooring device, a support, a mooring boom pivoted on a horizontal axis at its inner end to said support whereby the outer end thereof swings freely in vertical directions, a rigid non-flexible member secured at one end to the outer end of said boom and hingedly connected at its inner end to said support in spaced relation to the pivot of said boom thereby resisting lateral movement of said boom, a flexible supporting member connected at one end to the free end of said boom and at its other end to said support above said boom, a yieldable element in said flexible supporting member to enable the latter to extend or retract, and means on the free end of said boom to detachably secure a boat thereto.

15 20 25 30 35 40 45 50 55 60 65 70 75 80 85 90 95

4. In a boat mooring device, a support, a mooring boom comprising a pair of rigid members secured together at their outer ends and having their inner ends spaced apart, hinge members connecting said inner ends to said support whereby the outer end of said boom swings freely in vertical directions, a supporting member connected at one end to the free end of said boom and at its other end to said support above said boom, a yieldable element in said supporting member to enable the latter to extend or retract, and means on the free end of said boom to detachably secure a boat thereto.

4. In a boat mooring device, a support, a mooring boom comprising a pair of rigid members secured together at their outer ends and having their inner ends spaced apart, hinge members connecting said inner ends to said support whereby the outer end of said boom swings freely in vertical directions, a supporting member connected at one end to the free end of said boom and at its other end to said support above said boom, a yieldable element in said supporting member to enable the latter to extend or retract, and means on the free end of said boom to detachably secure a boat thereto.

5. In a boat mooring device, a support, a V-shaped boom, hinges connecting the spaced ends of said boom to said support, the axes of said hinges alined in a generally horizontal plane whereby the outer end of said boom swings freely in vertical directions, a supporting member connected at one end to the free end of said boom and at its other end to said support above said boom, a yieldable element in said supporting member to enable the latter to extend or retract, and means on the free end of said boom to detachably secure a boat thereto.
